(57) **CLAIM**

The ornamental design for a hammer stand as shown.

DESCRIPTION

FIG. 1 is a perspective view of an embodiment of a hammer stand having a removable adapter plate disposed on top, in accordance with our design;

FIG. 2 is another perspective view of the hammer stand of FIG. 1 with a small hammer therein;

FIG. 3 is a top perspective view of the hammer stand of FIG. 1;

FIG. 4 is a front view of the hammer stand of FIG. 1;

FIG. 5 is a rear view of the hammer stand of FIG. 1;

FIG. 6 is a right-side view of the hammer stand of FIG. 1;

FIG. 7 is a left-side view of the hammer stand of FIG. 1;

FIG. 8 is a top view of the hammer stand of FIG. 1;

FIG. 9 is a bottom view of the hammer stand of FIG. 1;

FIG. 10 is an enlarged view of a region of the bottom view of the hammer stand of FIG. 9;

FIG. 11 is an exploded perspective view of the hammer stand of FIG. 1 with the adapter plate detached from an optional top location;

FIG. 12 is an exploded perspective view of the hammer stand of FIG. 1 with the adapter plate detached from an optional side location; and,

FIG. 13 is a left-side view of the hammer stand of FIG. 1 with the removable adapter plate attached at the optional side location.

The dashed broken line(s) define unclaimed subject matter and form no part of the claimed design.

1 Claim, 10 Drawing Sheets
